Primary Examiner—Paula Greene(74) *Attorney, Agent, or Firm*—LaRiviere, Grubman & Payne, LLP(57) **CLAIM**

The ornamental design for pair of in ear headphones, as shown and described.

DESCRIPTION

FIG. 1 is a front perspective view of a pair of in ear headphones, showing our new design.

FIG. 2 is a front view thereof;

FIG. 3 is a rear view thereof;

FIG. 4 is a side view of one of a pair of in ear headphones shown separately for ease of illustration.

FIG. 5 is a side view of one of a pair of in ear headphones shown separately for ease of illustration.

FIG. 6 is a top view thereof; and,

FIG. 7 is a bottom view thereof.

The broken lines showing the environment in the Figures are for illustrative purposes only and form no part of the claimed design.
